GOLF CLUB HEAD

Wallace R. Hogan, 3838 SE. 58th Ave., Portland, Oreg.

Filed Jan. 30, 1964, Ser. No. 78,431

Term of patent 14 years

(Cl. D34—5)

I claim:

The ornamental design for a golf club head, as shown.
